Primary Examiner—Janice E. Seeger
Attorney, Agent, or Firm—Michael J. Kline; Darren E. Wolf[57] **CLAIM**

The ornamental design for panel for patio furniture, as shown and described.

DESCRIPTION

FIG. 1 is a perspective view of a panel for patio furniture, showing my new design, with the edges wrapped in condition for use; the broken lines are for environmental purposes only and form no part of the claimed design;

FIG. 2 is a front elevational view of the panel;

FIG. 3 is a rear elevational view of the panel;

FIG. 4 is a top plan view of the panel;

FIG. 5 is a bottom plan view of the panel;

FIG. 6 is a left side elevational view of the panel; and, FIG. 7 is a right side elevational view of the panel.
